his Attorney.

UNITED STATES PATENT OFFICE.

GUSTAV BECKER, OF CHICAGO, ILLINOIS.

SHIPPING-CRATE.

1,089,896.

Specification of Letters Patent. Patented Mar. 10, 1914.

Application filed July 25, 1912. Serial No. 711,558.

To all whom it may concern:

Be it known that I, GUSTAV BECKER, a citizen of the United States, and a resident of the city of Chicago, county of Cook, and 5 State of Illinois, have invented certain new and useful Improvements in Shipping-Crates, of which the following is a specification.

My invention relates to shipping crates 10 and more specifically to that class thereof designed for use especially in the shipment of bananas.

The object of my invention is the production of a crate of the character mentioned, 15 which will be of a foldable nature so that, when in use, the same may be folded together into compact form for convenience in storage or return shipment.

A further object is the production of a 20 shipping crate, as mentioned, which will be of durable and economical construction and efficient in use.

Other objects will appear hereinafter.

The invention consists in the combinations 25 and arrangements of parts hereinafter described and claimed.

The invention will be best understood by reference to the accompanying drawing forming a part of this specification, and 30 in which,

Figure 1 is a perspective view of the shipping crate embodying my invention, the same being shown arranged in distended or operative position, Fig. 2 is a plan view 35 of the crate in unfolded or inoperative position, Fig. 3 is a detail perspective illustrating the preferred form of construction for locking the crate in distended or operative position, Fig. 4 is a horizontal section of 40 the crate illustrating a modified form of construction for pivotally connecting the sections of the crate body, Fig. 5 is a perspective view of the lower end portion of the construction shown in Fig. 4, and Figs. 45 6 and 7 are views similar to Figs. 4 and 5 respectively, illustrating another form of construction for pivotally connecting the sections of the body.

The preferred form of construction as 50 illustrated in the drawing comprises a body consisting of a lateral wall which is formed of a plurality, preferably four in number, of rectangular sections 1. Each of the sections 1 is formed of a frame 2 and a foraminated or reticulate central portion 3 which is formed preferably of wire mesh as shown.

The contiguous edges of the sections 1 are pivotally connected by means of wires 4 which are secured to the transversely extending bearing portions of the frames 2 at the outer sides thereof, said wires being 60 secured to said frame members by means of staples 5. By thus connecting the sections 1, the latter will be permitted to be folded into rectangular form, as shown in Fig. 1, 65 or unfolded into co-planar positions for storage or return shipment, as shown in Fig. 2. Said sections are secured in folded or operative positions by the provision of co-operating hooks and eyes 6 and 7 provided 70 at the respective ends of the wire members 4, as clearly shown in Fig. 2. If desired, the extremities of wire members 4 may be fastened together in the manner shown in Fig. 3, in which event the respective extremities 75 of said wire members will be formed with loops 8 adapted to interlock with each other, a seal 9 of any ordinary or preferred construction being adapted for employment in locking the loops 8 in engaging position, 80 as will be readily understood. Also if desired, the wire members 4 may be formed in sections, each section being of a length corresponding with the width of the corresponding body section 1, the contiguous extremities of said wire section, in this arrangement, being pivotally fastened together by providing the same with interlocking loops, as clearly shown in Figs. 4 and 5. Also if desired, the wire member 4 may be 85 dispensed with and in lieu thereof hinges 10 employed for pivotally securing the sections 1 together, as clearly shown in Figs. 6 and 7, a lock 10' of any desired construction being provided, in this event, to lock 95 the sections in operative position.

Pivotally secured to the lower end portion of one of the sections 1 is a bottom 11 adapted, when in use, to be supported at its outer or free end upon the cross-piece at the lower 100 end of the diametrically opposite section 1, as clearly shown in Figs. 4 and 6. When the crate is in unfolded condition, bottom 11 may be folded to position between the longitudinal frame members of the section 1 carrying said bottom, as clearly shown in Fig. 2.

Provided at the upper edges of the sections 1 is a flexible sheet or strip 12 formed preferably of fabric, the latter being adapted, when the crate is in operative position, to 110 be gathered together and secured by means of a cord 12' in order to constitute a closure

for the crate, as clearly shown in Fig. 1. When the crate is not in use said member 12 may be positioned substantially co-planar with the sections 1 in order to permit of packing of the crates in small compass as will be readily understood.

Within the crate body is provided a circular inner wall 13 formed preferably of a sheet of cardboard which is bent upon itself 10 into tubular or cylindrical form, said inner wall serving as a means of insuring against injury to the fruit by reason of contact thereof with the rough or unfinished surfaces of the crate sections 1. The member 15 13, when the crate is unfolded, may be bent straight so as to lie flat upon the upper side of the crate body when in flat or unfolded condition.

A crate of the construction set forth is 20 durable and economical in construction, the same may be collapsed into compact form for storage or return shipment after the contents thereof have been removed, and the construction is such as to be highly efficient in 25 use.

While I have illustrated and described the preferred form of construction for carrying 30 my invention into effect, this is capable of variation and modification without departing from the spirit of the invention. I, therefore, do not wish to be limited to the exact details of construction set forth, but desire to avail myself of such variations and 35 modifications as come within the scope of the appended claims.

Having described my invention, what I claim as new and desire to secure by Letters Patent, is:

1. A shipping crate comprising a plurality 40 of sections pivotally connected together;

a bottom hingedly secured to one of said sections; a flexible closure secured to the upper ends of said sections; and a tubular flexible wall loosely positioned within said crate and adapted when removed to be unfolded to 45 assume a flat form, substantially as described.

2. A shipping crate comprising a body consisting of a plurality of sections pivotally connected together at their vertical edges, 50 one pair of said edges being detachably connected to permit of unfolding of said sections; a bottom hingedly connected with one of said sections; and a sheet of flexible material arranged in tubular form loosely positioned in said body to constitute an inner wall therefor, said sheet being adapted, when said body is unfolded, to be unwound into straight form to lie flat against said body, 55 substantially as described. 60

3. A shipping crate comprising a body consisting of a plurality of sections pivotally connected together at their vertical edges, 65 one pair of said edges being detachably connected to permit of unfolding of said sections; a bottom hingedly connected with one of said sections; and a substantially rectangular sheet of cardboard arranged in tubular form to constitute an inner wall therefor, said sheet being adapted, when said body 70 is unfolded, to be unwound into straight form to lie flat against said body, substantially as described. 75

In testimony whereof I have signed my name to this specification in the presence of two subscribing witnesses.

GUSTAV BECKER.
